AMUSEMENT RIDE

John N. Bartlett, Tonawanda, N. Y.

Application November 26, 1934, Serial No. 754,803

8 Claims. (Cl. 272—49)

This invention relates to an amusement ride or apparatus designed for use in amusement parks, playgrounds and the like to simulate the thrill of looping the loop.

- 5 It has for its object to provide an amusement apparatus of this character which is so designed and constructed as to enable the passenger or passengers to readily manipulate it, and which affords maximum safety to the passengers.
- 10 Another object of the invention is the provision of a looping apparatus having simple and effective means for arresting its movement after the completion of a ride, and to provide means associated with the arresting means for automatically governing the same to control the duration of the ride.

15 A further object is to provide an amusement ride which is so constructed and balanced as to enable the passengers through their own efforts to operate the same in a vertical circle to loop-the-loop, and which is strong and durable in construction and safe and positive in operation.

20 A still further object is to provide the apparatus with mechanical means for assisting the passenger or passengers in effecting the looping of the apparatus.

25 Other features of the invention reside in the construction and arrangement of parts herein-after described and particularly pointed out in the appended claims.

30 In the accompanying drawings:

35 Figure 1 is a side elevation of an amusement apparatus embodying my invention. Figure 2 is an end view thereof, partly in section. Figure 3 is an enlarged longitudinal section of the passenger carriage taken substantially in the plane of line 3—3, Figure 2. Figure 4 is a cross section taken in the plane of line 4—4, Figure 3. Figure 40 5 is an enlarged transverse vertical section taken substantially in the plane of line 5—5 Figure 1. Figure 6 is a detailed sectional view of the timing element or air cylinder associated with the brake mechanism. Figure 7 is a fragmentary side view of the apparatus showing a modification of the booster mechanism. Figure 8 is an enlarged transverse vertical section taken substantially in the plane of line 8—8, Figure 7. Figure 9 is a cross section taken on line 9—9, Figure 8. Figure 10 is a front elevation of a modified form of the amusement ride. Figure 11 is a fragmentary end view thereof.

45 Similar characters of reference indicate corresponding parts throughout the several views.

50 By way of example, my amusement ride has been illustrated in the drawings in the form of a single unit, but in practice a plurality of series of such units may be employed with the units disposed side by side.

55 60 Referring now to Figures 1—6, inclusive, the

apparatus comprises substantially upright side frames or standards disposed in spaced relation and each consisting of an upright central member 10 and inclined side members 11, longitudinal base members 12, longitudinal tie members 13 parallel with the base members and connected to said central and side members in the manner shown in Figure 1, and a transverse tie member 14 connecting the upper ends of the central members 10. Adjacent its opposite ends where the passengers are admitted to and discharged from the apparatus, there are provided platforms 15 between the base members 12.

5 10 15 20 25 30 35 40 45 50 55 60 Suspended in the space between these standards for swinging movement in a substantially vertical circular path to simulate looping the loop, is a passenger car or carriage 16 designed to receive one or more passengers in a standing position, the carriage while revolving about a given axis being held against turning so that the passengers always assume an upright or standing position during the oscillating and looping movement of the carriage. This carriage in its preferred construction shown in the drawings, is in the form of a substantially cylindrical cage-like structure made of screening or other foraminous material so that the passengers may look out and also be seen by spectators, and is provided at its diametrically opposite sides with ingress and egress openings 17 normally closed by vertically swinging doors 18 hinged at 19 and each having a yielding tie member 20 which serves to either hold the door in its lowered or closed position, shown by full lines in Figure 3, or in its open or elevated position shown by dotted lines in such figure. In its bottom the carriage has a platform 21 on which the passengers stand during the ride and extending diametrically across the carriage adjacent the opposite sides thereof are handle bars 22 which are adapted to be grasped by the passengers. Adjacent the door-openings 17 are transversely-extending safety bars 23 which are pivoted at one end of the handle bars 22 and which rest at their free ends on the companion handle bar in the manner shown in Figure 4. Associated with each safety bar is a latch-bolt 24 guided for sliding movement in a bracket 25 mounted on one of the handle bars 22 and adapted at its inner end to releasably engage the corresponding safety bar 23 to hold it in its safety or horizontal position when the door 18 is closed. The door is adapted to abut and engage the outer end of the latch bolt to force it into engagement with the safety bar and hold it there during the time the door is closed, a spring 26 applied to the bolt serving to urge the latter to its released position when the door is open. In order to positively hold the door in its closed position, swinging latch hooks 27 may be employed which

engage corresponding studs 26 upon the carriage, springs 29 acting to hold the latch hooks in latched position. When it is desired to admit passengers to or discharge them from the carriage, the attendant swings the latch hooks to their released position, opens the door 18 and lifts the safety bar 23, which is automatically released when the door is opened.

The carriage 16 is so suspended from the standards that it has a motion of translation in a substantially circular path, whereby its platform 21 remains parallel to itself in all positions of the carriage and the passengers always assume an upright position. As shown in Figures 1 and 2, the carriage is suspended at its opposite sides from a plurality of revolving arms 30, 31, 32 which are fulcrumed intermediate their ends at suitably spaced points on the standard. In the drawings, these arms are shown 20 fulcrumed at triangularly spaced points 33, 34, 35, the pivot spindles 33 and 34 of the arms 30, 31 being applied to the horizontal frame members 13 at equidistant points on opposite sides of the central upright frame member 10 and the pivot spindles 35 of the arms 32 being mounted on said member 10 above and centrally between the companion pivot spindles 33, 34, whereby, when the carriage is in its lowest position to receive and discharge passengers, as seen by dotted lines in Figure 1, the several arms are in a pendant parallel position and equally spaced. At their lower ends, these arms are connected to the carriage by suitable pivots 36 disposed adjacent the periphery thereof and at triangularly-spaced points thereon, the distances between the arm-pivots and the carriage-pivots of the respective arms being the same. Fitted about the pivots 36 are bushings 36^a of rubber or like material which allow for the proper mechanical movements of the suspension arms without strain and afford a smooth turning of the carriage. The opposite or free ends of the suspension arms are provided with weights 37 which are preferably of such moment as to not only counterbalance the carriage but to slightly overbalance it, and thereby minimize the efforts required of the passenger or passengers to swing the carriage through a complete circle or to cause it to loop. As seen in Figure 2, the suspension arms 50 are laterally offset to permit their relative clearance during the rotation of the arms about their respective pivots.

Means are provided for arresting the movement of the carriage 16 at its lowest position for 55 the ingress and egress of passengers, and for this purpose one of the suspension arms, say the arm 30 is provided concentrically of its pivot-spindle 33 with a brake drum 38 which is bolted or otherwise fixedly secured to the suspension arm to revolve therewith. Cooperating with this brake drum is a brake band 39 carried by a vertically-swinging arm 40 pivoted to the adjoining portion of the frame structure and having a spring 41 connected thereto for constantly urging the arm 40 in a direction to apply the brake. For swinging the arm to a brake-releasing position, a hand lever 42 is provided which is connected by a link or links 43 with the free end of the arm 40.

Associated with the brake mechanism in opposing relation to the spring 41 is a time element for automatically effecting the application of the brakes after a predetermined time, whereby each passenger is assured a ride of a given dura-

tion. This time element is preferably in the form of an air cylinder 44 having a leather cup plunger 45 therein whose rod 46 is connected with the brake lever 42 and by the links 43 with the brake arm 40, as shown in Figures 1 and 6. At its discharge end this cylinder has an adjustable vent or port 47 controlled by a threaded stem or bolt 48 which allows for the gradual escape of the air from the cylinder after the brake lever has been shifted to its released position, and effects, in conjunction with the spring 41, the gradual return of the arm 40 to its brake-applying position. A pet cock 49 may also be provided on the cylinder to effect an emergency application of the brake should the occasion arise.

In some cases the passengers may not have that physical control in the use of their bodies, as knee-bending and other body effort, to impart that motion to the carriage to effect its looping. To assist the passengers of this type, I provide a selectively-controlled power or mechanical booster mechanism which functions to assist the turning of the arms 30, 31 and 32 to quickly bring the carriage to the proper degree of swing to loop, and which is preferably controlled by the attendant of the apparatus. As seen in Figure 1, this booster mechanism consists of an electric motor 58 suitably supported at the base of the frame structure and having a sprocket 51 connected by a chain 52 to a sprocket 53 applied to the brake drum 38. Associated with the sprocket 51, is a suitable clutch 54 controlled from the operator's station of the machine by a hand lever 55. When the clutch is engaged, motion is transmitted to the sprocket 53 to compel the turning of the arm 30 about its fulcrum 33 and likewise the swinging of the carriage and the turning of the companion arms 31 and 32 about their respective fulcrums. When the required momentum has been transmitted to the carriage 16 in this manner, the operator then disengages the clutch to allow the carriage to move under its own momentum.

In Figures 7, 8 and 9 I have shown a manually-operated mechanism for effecting a boosting movement to the carriage, the same including a drum 56 fixedly secured to one of the suspension arms, say the arm 31, to revolve therewith about its pivot spindle 34 and a brake shoe 57 cooperating therewith and pivoted at 58 to a crank 59 of an actuating lever 60 which is fulcrumed at 61 to an arm 62 rotatably mounted on a frame-fitting member 63 of the companion pivot spindle 34. A spring 64 connected to the actuating lever 60 serves to constantly urge it in a direction to bring the brake shoe 57 out of engagement with the drum 56, the lower end of said lever having a stop lug 65 thereon adapted to abut against the opposing side of the arm 62 to limit the movement of the lever to its released position. The numeral 66 indicates a booster lever connected by a link 67 with the actuating lever 60, so that when the booster lever is pulled downwardly it brings the brake shoe 57 in frictional contact with the brake drum 56 and the further movement of the booster lever turns the brake drum to in turn impart a turning movement to the suspension arm 31 to increase the momentum of the carriage and cause it to loop. When the boosting effort has been transmitted in this manner, the lever 66 is released and the spring 64 returns it and the associated parts to their released position. The return of the lever 60 and its supporting arm 62 is limited by a stop 68 secured to the frame member 13, as shown in

Figure 9. When the arm 62 encounters this stop, it effects a toggle action and causes the lever 60 to swing about its pivot 61 in a direction to lift the shoe 57 from the drum 56.

5 In the modification of the ride shown in Figures 10 and 11, the passenger carriage 69 is pivoted substantially centrally thereof, as indicated at 70, to the lower end of a rotatable suspension arm 71 fulcrumed intermediate its ends at 72 to the frame structure 73. At its upper end this arm is counter-weighted preferably by a fluid-chamber 74. During the swinging of the suspension arm, the carriage is adapted to have a motion of translation and to this end the pivot-shafts 70 and 72 have bevel gears 75 thereon which mesh with pinions 76 applied to the upper and lower ends of a shaft 77 journaled in bearings 78 fixed on the arm 71, as shown in Figure 11. A rocking motion is transmitted to the arm 20 from an electric motor 79 or other source of power through the medium of forward and reverse clutch-controlled gears 80 meshing with a pinion 81 fixed on the lower end of an upright shaft 82 suitably journaled on the frame 73. At 25 its upper end this shaft has a pinion 83 thereon meshing with a gear 84 fixed on the arm-fulcrum shaft 72, which latter is keyed or otherwise secured to the arm 71. The pivot-shaft 70 of the carriage is keyed thereto so that as the arm 71 30 is rocked and looped the carriage will assume a motion of translation and take a horizontal position in all positions of the arm. The clutch members associated with the gears 80 are indicated at 85 and may be controlled by a hand 35 lever 86.

I claim as my invention:—

1. An amusement apparatus, comprising a frame, suspension arms pivoted intermediate their ends to said frame at substantially triangularly spaced points, and a passenger carriage pivotally connected at spaced points thereon to the companion ends of the arms to revolve bodily about the pivots thereof, the distances between the arm-pivots and the carriage-pivots of the 45 respective arms being the same, and the opposing free ends of said arms having weights thereon to at least counter-balance the weight of the carriage.

2. An amusement apparatus, comprising a frame, a plurality of swinging arms pivoted intermediate their ends to said frame to swing in a substantially vertical plane, and a passenger-carriage pivotally suspended at triangularly-spaced points from one end of said arms to have 55 a motion of translation in a substantially circular path during the swinging of the arms, the opposite ends of said arms being weighted to substantially counterbalance the carriage.

3. An amusement apparatus, comprising a passenger-carriage, means for pivotally suspending said carriage to have a motion of translation in a substantially circular path, braking means for arresting the movement of the carriage, means for normally actuating the braking means to its applied position, and timed brake-delaying means interposed in operative relation with the brake actuating means to actuate said braking means after a predetermined duration of the ride.

4. An amusement apparatus, comprising a frame, a plurality of swinging arms pivoted to said frame to swing in a substantially vertical plane, a passenger-carriage pivotally suspended

from said arms to have a motion of translation in a substantially circular path during the swinging of the arms, a brake drum applied to one of said arms concentrically of its pivot, a brake band engageable with said drum, lever means for actuating said band including a spring for normally urging said means to a brake-applying position, and a time-controlled device including a fluid-containing cylinder and piston interposed in said leverage means in opposing relation to the spring for governing the automatic application of the brake band. 10

5. An amusement apparatus, comprising a pivoted, rotatable suspension means consisting of a plurality of parallel, vertically-swinging arms, 15 a passenger carriage of cage-like form pivoted at its periphery to said arms for a motion of translation in which the carriage is in a horizontal position at all times during the movement of said suspension means initiated by the passenger, and means assisting the manual efforts of the passenger for selectively imparting rotary movement to said suspension means to effect the looping of the carriage. 20

6. An amusement apparatus, comprising a pivoted rotatable suspension means consisting of a plurality of parallel, vertically-swinging arms, a passenger carriage of cage-like form pivoted at its periphery to said arms for a motion of translation in a substantially circular path during the 25 movement of said suspension means initiated by the passenger and in which the carriage is in a horizontal position at all times, a driven member rotatable with the suspension means about its pivot, and selectively-controlled means assisting the manual efforts of the passenger and operatively connected to said driven member for transmitting motion thereto to impart a boosting movement to the suspension means and its carriage. 30

7. An amusement apparatus, comprising a pivoted rotatable suspension means, a passenger carriage mounted thereon for a motion of translation in which the carriage is in a horizontal position at all times, the movement of said suspension means being normally initiated by the passenger, a driven member rotatable with the suspension means about its pivot, a manually-actuated lever including releasable means for coupling it with said driven member for transmitting motion thereto to impart a boosting movement to the suspension means and its carriage, and means for constantly urging said lever and its coupling means to a released position. 45

8. An amusement apparatus, comprising a frame, a plurality of swinging arms pivoted intermediate their ends to said frame to swing in a substantially vertical plane, a passenger-carriage of substantially cage-like, cylindrical form pivotally suspended at triangularly-spaced points from the lower ends of said arms to have a motion of translation in a substantially circular path during the swinging of the arms, said carriage being adapted for actuation by the passenger, means applied to the upper ends of said arms for overbalancing the weight of the carriage and tending to swing it past the vertical, and brake means for arresting the movement of the carriage and maintaining it in line with the vertical when loading and unloading passengers. 55

JOHN N. BARTLETT.
